CHARLES M. GREY, OF EAST ORANGE, NEW JERSEY, ASSIGNOR TO NEW YORK STEEL BEAM & GIRDER COMPANY, OF NEW YORK, N. Y., A CORPORATION OF NEW YORK.

ART OF ROLLING.

968,464.

Specification of Letters Patent. Patented Aug. 23, 1910.

Application filed September 4, 1908. Serial No. 451,721.

To all whom it may concern:

Be it known that I, CHARLES M. GREY, a citizen of the United States, residing in East Orange, county of Essex, and State of New Jersey, have invented a certain new and useful Improvement in the Art of Rolling, of which the following is a specification.

This invention is a process of, and apparatus for, rolling flanged shapes, such as I and H beams, girder beams, columns and channels, and is of particular value in rolling sections of the character specified when it is desired that the inner faces of the flanges on said sections shall be inclined at an obtuse angle to the web. When the flanges are "straight," or, in other words, form a right angle with the web, no special difficulty exists in rolling them by the methods and apparatus heretofore employed. Furthermore, the invention is of special importance in rolling sections of the character specified when it is desired to produce sections wherein the mean thickness of the flanges, compared with the thickness of the web, is comparatively great; or, in other words, produce sections having webs that are thin compared with the mean thickness of the flanges. It has been found to be practically impossible to roll sections of this latter character by the methods and apparatus heretofore devised, owing to the tendency of the section to spread, i. e., widen at the flanges, or of the web to buckle. My invention overcomes these difficulties and enables beams, of the character specified, to be rolled expeditiously and satisfactorily, and, accordingly, is a pronounced advance in the art.

The invention enables me to produce, from properly shaped blooms or bars, I-beams, H-beams, girder beams, channel bars, etc., free from buckled webs and other injurious defects, upon a type of universal mills provided with horizontal and vertical rolls, all the axes of which are in the same plane, and the working surfaces of whose vertical rolls are substantially at right angles to the web working surfaces of the horizontal rolls.

The process consists, mainly, in passing the bar under manipulation and without at any time turning it, several times through one train of universal rolls, the two pairs of horizontal rolls of which have their sides which are contiguous to the inner contour of the flanges at an angle to the axis of the

web producing faces, such angle being the same on both of the said pairs of horizontal rolls; then passing the bar one or more times through another train of universal rolls, the two pairs of horizontal rolls of which have their sides which are contiguous to the inner contour of the flanges at an angle to the web producing faces which is less obtuse than the corresponding angles of the first universal train of rolls, this latter angle, i. e., the less obtuse angle being substantially the same on both pairs of horizontal rolls forming part of the second universal train of rolls. It is to be understood that the working surfaces of all vertical rolls are always substantially at right angles to the web working surfaces of the horizontal rolls.

In the accompanying drawings I have illustrated one practical embodiment of the apparatus forming part of the invention, and capable of use in practicing my process, but the construction shown therein is to be understood as illustrative, only, and not as defining the limits of the invention. For example, the mill or apparatus forming the subject matter of my co-pending application, Serial No. 451,722, filed September 4, 1908, is particularly adapted for carrying out the process herein disclosed.

Figure 1 is a diagrammatic plan view of one of the arrangements of roll trains that may be employed for the production of flanged I, H, girder, or channel-shaped bars; Fig. 2 is a front view of a universal rolling mill adapted for rolling the hereinbefore mentioned sections; Fig. 3 is an enlarged view of one of the horizontal rolls used in stand, C, Fig. 1. Fig. 4 represents, approximately, in full lines a partially rolled beam section as it leaves the first train of rolls, and the dotted lines show, approximately, the contour of the same beam section as it appears after passing once through the finishing or second train of rolls. Fig. 5 is an enlarged view of the horizontal rolls used in stand, E, Fig. 1; the outlines of the horizontal rolls used in stands, C, E, Figs. 3 and 5, being shown for the purpose of illustrating the particular feature of construction employed in any two consecutive sets of universal mills used in carrying out my process.

Referring particularly to Fig. 1, A is the "blooming" or blank shaping mill; C is

the first main mill, and coöperating therewith is the supplementary or flange edge rolling mill, B; E is the second main mill, and, coöperating therewith is the second 5 supplementary or flanged edge rolling mill, D. For the purpose of explaining the invention, I have not deemed it necessary to illustrate more than two main mills, with their corresponding supplemental mills, 10 though it will of course be understood that three or more mills may be used if desired. It will be understood, moreover, that the invention is not restricted to the employment of the supplementary mills in conjunction 15 with the main mills.

Supplementary mills, B and D, which regulate the width of the flanges contain, only, two horizontal rolls, while the main trains, or universal mills, C and E, each 20 contain four working rolls as hereinafter described. It will, of course, be understood that the first set of universal rolls, C, is employed to successively reduce, after successive adjustments of the horizontal and vertical rolls, the cross sectional area of the bar until it is reduced to the size desired, or nearly finished, when the second set of universal rolls, E, are used to finish the bar 25 by similar successive rollings, the horizontal and vertical rolls being properly adjusted after each passage of the bar through the same.

A shear or saw is shown at F, for cutting off crop ends, and, as is usual, the various 30 sets of rolls are provided with tables, G, for properly feeding the pieces operated upon.

The mill, A, is for shaping ingots into a blank or shape suitable for entry into the first supplementary and main mills, B and 40 C, respectively. These reduce the shapes into bars of smaller cross sectional area and with the angle of the inner contour of the flange greater than it will be after the bar has passed through the succeeding sets of 45 rolls, D and E, respectively. The bar having passed through the rolls of mills "B" and "C", and having been reduced sufficiently, is carried forward, by means of tables, G, to roll trains, D and E, the rolls of these 50 trains having the angles forming the inner contours of flanges smaller than the corresponding angles of the preceding set.

In Fig. 2, I have illustrated an universal mill, such as is shown in diagram by C and 55 E, in Fig. 2, H and I, representing the horizontal rolls, K and L, the vertical rolls, and, m, the piece being operated upon. The various adjusting mechanisms for the rolls, as well as the driving connections, being 60 well known, it is not thought necessary to refer to them in detail. With the main horizontal rolls, such as H and I, of each mill, operating to reduce the thickness of the web and also in conjunction with the 65 vertical rolls, such as K and L, operating to

reduce the flange thickness, the bar is finally brought to the proportion and shape desired.

Fig. 3 shows, approximately, the contour of horizontal rolls in train, C, while Fig. 5 70 shows, approximately, the working parts of horizontal rolls in train, E. It will be observed that while the angles of inclination of the side working faces of horizontal rolls in main train, C, are greater than the corresponding angles in the rolls of main train, E, the width of the web producing surfaces, in the former are less than in the latter; in other words, rolls in train, E, have wider web-rolling portions than the rolls in train, 75 C. The construction of rolls in mills, C, E, as described, is what enables me to accomplish my desired results. The surfaces of the two horizontal rolls in supplementary mill, B (the only rolls in said mill), which 80 bear upon the inner sides of the flanges of the bar, have the same taper, preferably, as the surfaces of the horizontal rolls in its co-operating main mill, which latter rolls do the work on the inner surfaces of the flanges. 85 The same is true of the rolls in supplementary mill, D, with respect to the horizontal rolls in main mill, E.

Fig. 4 represents in full lines, approximately, the contour of the rolled beam section after it leaves the rolls in mill, C, and, in dotted lines, substantially its contour after having been operated upon by the rolls in mill, E. It will be observed that in both instances the inner faces of the flanges are inclined, or, in other words, make obtuse angles with the webs.

It will be understood that in all universal mills, of the character hereinbefore described, such as C and E, the horizontal rolls work on 95 both sides of the web and the inner sides of the flanges, and the vertical rolls work on the outer side of the flanges at each passage of the bar through the mill; the supplementary rolls working on the edges of the flanges 100 of the bar.

My invention is not restricted to the details described, but, as will be understood by those skilled in the art, may be modified within the scope of the appended claims.

Having thus fully described the invention, what I claim as new, and desire to secure by Letters Patent is:

1. In the art of rolling channelled beams or sections, the process which consists in successively passing the piece under manipulation through a universal train of rolls having horizontal and vertical rolls whose axes are in the same plane, the working sides of each horizontal roll being inclined at an obtuse angle to a horizontal plane passing through the axis of said roll, and then successively passing the piece through a second universal train having horizontal and vertical rolls whose axes are in the same plane, 115 120 125 130

and wherein the corresponding obtuse angle of the working sides of each horizontal roll is less than that in the first mill, thus securing a greater reduction in the thickness of 5 the root of the flanges than is obtained at the points of said flanges.

2. In the art of rolling channeled beams or sections, the process which consists in successively passing the piece under manipulation through a universal train of rolls having horizontal and vertical rolls the axes of which are in the same plane, and wherein the working side faces of each horizontal roll are inclined at an obtuse angle to 10 a horizontal plane passing through the axis of said roll, the width of the web rolling surfaces of said mill remaining substantially the same during the successive passes of the piece, and then successively passing 15 said piece through a second universal mill having horizontal and vertical rolls the axes of which are in the same plane, and wherein the corresponding obtuse angle of the working side faces of each horizontal roll is less 20 than that in the preceding mill, the width of the web rolling surfaces of said second mill remaining substantially the same in each of 25 the passes of the piece therethrough.

3. In the art of rolling channeled beams or sections, the process which consists in passing a suitably prepared bloom or blank through a universal mill embodying horizontal and vertical rolls the axes of which are in the same plane alternately in one direction and then in the opposite direction, and in which mill the sides of the two horizontal rolls, contiguous to the inner contour of the flanges on the piece being rolled, are inclined at an obtuse angle to the web producing faces, then passing said piece to and fro through another universal mill having the axes of its horizontal and vertical rolls in the same planes respectively as the axes of the corresponding rolls of the first universal mill, the two pairs of horizontal rolls of which second mill have their sides, contiguous to the inner contour of the flanges on the piece, inclined at an angle to the web producing faces less obtuse than those on 50 the first universal mill.

4. In the art of rolling channeled beams or sections, the process which consists in passing a suitably prepared bloom or blank through a universal mill embodying horizontal and vertical rolls the axes of which are in the same plane, alternately in one direction and then in the opposite direction, and in which mill the sides of the two horizontal rolls, contiguous to the inner contour

of the flanges on the piece being rolled, are 60 inclined at an obtuse angle to the web producing faces, the web rolling faces in said mill being of the same width during all of the said passes, then passing said piece to and fro through another universal mill having horizontal and vertical rolls the axes of which are in the same plane, the two pairs of horizontal rolls of which have their sides contiguous to the inner contour of the flanges on the piece, inclined at an angle to 65 the web producing faces less obtuse than those on the first universal mill, the web rolling surfaces in said second mill being the same for all the passes therethrough, and yet wider than the web rolling surfaces in 70 the first universal mill.

5. The combination of a universal mill comprising horizontal and vertical rolls so positioned that their axes are in the same plane, the said horizontal rolls having tapering sides, and a second universal mill comprising horizontal and vertical rolls so positioned that their axes are in the same plane, the horizontal rolls of said second mill having tapering sides of such taper that the 80 web rolling surface is more than the corresponding surface in the first mill, the vertical rolls of said second mill being closer together than the corresponding rolls of the first mill whereby the entire section rolled 85 thereon is narrower than when it left the first universal mill.

6. The combination of a universal mill having horizontal and vertical rolls the axes of which are in the same plane, through 90 which a suitably shaped blank may be rolled alternately in one direction and then in the opposite direction therethrough, and in which mill the web reducing roll has tapered sides, the width of the web producing surface on said roll being the same in all of 95 said passes, and a second universal mill having horizontal and vertical rolls the axes of which are in the same plane and wherein the web reducing roll is wider than the corresponding surfaces of the first mill, the body of the rolls on said second mill being narrower than those of the preceding set, if measured at a point near to where the outer 100 ends of the flanges are rolled.

In testimony whereof I have signed my name to this specification in the presence of two subscribing witnesses.
